UNITED STATES PATENT OFFICE.

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE.

PRESS FOR CUTTING OR PUNCHING SHEET MATERIAL.

Application filed July 30, 1927. Serial No. 209,497.

This invention is a novel press for cutting or punching sheet material. It relates particularly to the class of press adapted for dieing-out leather or similar sheet material to constitute the uppers or other parts of shoes or other articles, and is shown applied to the type of power operated press, which has come to be known as a clicking press, or clicker, which embodies a bed or cutting block 10 for supporting the leather and a presser or head movable or swingable laterally to selected positions over the leather and then movable down by power to effect the cutting or punching, usually by means of a loose die placed selectively upon the leather. A typical instance of a clicking press is the well known Reece clicker as illustrated, for example in U. S. Letters Patent 1,228,834 of June 5, 1917, this clicker being characterized by 15 the fact that the upright sliding post or pillar which carries the presser head down and up is not rotatable, the presser head being mounted to rotate upon the post, and having an upper or main rotary bearing upon the post, 20 with a rigid downward extension to a lower bearing upon the post. The herein illustrated embodiment of the present invention is shown applied to a clicking press so characterized, although the principles may to some extent 25 be utilized in clickers of other constructions, or in other types of press.

The general object of the present invention is to improve the convenience and efficiency of presses of the class and type referred to. A 30 particular object is to facilitate the manual work of laterally swinging the presser head, by substantially reducing its mass and inertia, without unduly sacrificing either the strength and rigidity of the iron presser head constructions heretofore customarily used, or the relatively low cost of such presser heads. The heavy mass and inertia of the presser head could of course be reduced by the substitution for iron of any material or metal of lower 35 specific gravity or mass, so long as it substantially retains the qualities possessed by iron of rigidity sufficient to communicate the cutting pressure, strength to avoid fracture and hardness to resist deformation. It is obvious and long well understood in the metals industries that aluminum is the ideal metal for the reduction of mass and inertia to the

lowest possible amount, and this material has been used in many situations, both in power driven machinery, and in manually operated 55 implements, for reduction of inertia and muscular effort. The widespread use of aluminum however, in machinery, has been somewhat hampered until recently by the lack of a suitable alloy possessing rigidity, strength 60 and hardness. The development of several such alloys has now made this metal industrially available for a far wider utility where lightness or low mass has been desirable, especially in industries, such as aviation and 65 high speed engines, where the high expense of the lighter metal has not been a factor. With a large casting such as the head of a clicking machine the expense of aluminum has heretofore been prohibitively high, especially 70 with the Reece type of clicker, so much so that the replacement of iron by aluminum alloy for the entire presser head involves an additional cost of a large amount, rendering 75 the substitution prohibitive in a commercial 80 sense.

With these considerations in mind it is a further object of the present invention to afford the maximum advantages and minimum disadvantages, through a composite 85 presser head, that is, built up of permanently related and connected parts of heavy and light materials, such as cast iron and cast aluminum alloy respectively, which will afford the desired low mass and inertia without sacrificing the desirable qualities previously mentioned. In the particular embodiment herein disclosed the presser head shape or body is built up of iron portions so arranged or located as to receive the greater 90 part of the compression stresses, and portions of any strong, rigid, hard aluminum alloy so arranged or located as to receive the tensile stresses, or the greater part thereof, these metals being respectively well adapted 95 to resist these respective strains. A properly designed presser head according to the principles hereof will afford low mass and inertia, while giving a degree of strength and rigidity practically inferior neither to an all iron 100 head nor an all aluminum alloy head, and having the hardness of the best aluminum alloy. Indeed, relieving the iron component of the tension stresses permits the same to

be cut down in cross section and so minimized in weight, thus keeping low the total weight of the presser head, cast iron being peculiarly well adapted to resist compression strains while unreliable for tensile strains, except with thick sections.

As herein specifically designed and constructed the composite presser head is further advantageous in avoiding the weaknesses which are inherent in producing castings of large section or bulk due to the shrinkage and foundry stresses developed therein; and the built up presser head of this invention gives the kind of strength and resistance inherent generally in built up structures such as trusses.

Other and further objects and advantages of the present invention will be referred to in the hereinafter following description of an illustrative embodiment of the invention or will be apparent to those skilled in the subject. To the attainment of such objects and advantages the present invention consists in the novel press or clicking machine, and the novel features of combination, construction, arrangement, design and detail herein illustrated or described.

In the accompanying drawings Fig. 1 is a right elevation of a clicking press generally similar to that disclosed in said prior Patent 1,228,834, but with the features of the present invention illustratively incorporated therein.

Fig. 2 is a top plan view of the presser head of Fig. 1, detached from the machine.

Fig. 3 is a vertical section taken on the line 3—3 of Fig. 1, looking from the front.

Fig. 4 is a horizontal section taken on the line 4—4 of Fig. 1, looking from above.

First will be described the general features which are also disclosed in the prior patent. Above a four legged base 10 is the main frame 11 supporting the cutting block or bed 12 which may comprise sections of wood held together by clamps 13 and mounted on an adjustable support 14. The swinging presser or head 15, located above the bed, is provided at its forward end with a suitable handle 16 for swinging it right and left.

A sheet of leather L is shown resting on the bed and a loose die 17 is placed thereon with its cutting edge against the leather so that the descent of the presser will press the die through the material, as is usual in clicking presses. The down and up movements are communicated to the presser through an upright post, ram or pillar 18 carrying the presser. The presser is formed with an upper bearing 19 on the post and a downward extension 20 extending to a lower bearing 21 also shown engaging the post. The post has a shoulder 22 at its top end confining the presser against upward movement, while a thrust bearing 23 is interposed between the presser and a collar 24 clamped upon the

post. The post slides up and down, being fitted within heavy fixed frame bearings 27 and 28. Power may be supplied through a belt pulley 30 normally loose but adapted to be clutched to a main shaft 31, usually for a single rotation, so that the presser head will descend for a cutting operation, rise, and come to rest. The shaft may carry an eccentric 32 which operates through a strap and rod 35 to pull down and force up the post and presser. The one rotation clutch may be of any type, such as that shown in the prior patent, which involves certain enclosed parts, including a clutch dog which has a pin 48 projecting outwardly in the path of a clutch cam or shoe 49 mounted at the lower end of a swinging clutch lever 50, an upper extension 54 of which is pulled by spring 55 to press the clutch into operative position so as to throw off the power and stop the shaft. The clutch may be released at will through a connecting rod 58 extending from the clutch shoe 49 to the upper end of a rock arm 59 mounted on a rock shaft 60 carrying also forwardly extending rock arms 61 connected by a cross connection or bar 62 which may serve as a pedal, while upward rods 63 extend to a controlling handle or bar 64 mounted within easy reach, at the forward end of supporting arms 65. The operation of these or equivalent parts may be substantially as described in said patent, or otherwise, a depressing movement of the hand bar 64, for example, serving to release the clutch, thus permitting engagement and drive for a single rotation of the shaft, which operates to pull down and again elevate the post and presser head, leaving them again in their normal or raised position as shown, assuming that the controller has in the meanwhile been released or the clutch otherwise set for stoppage.

In the operation of a clicking machine the presser head is subjected to forces or stresses of very considerable amount, tending to bend it, which itself is objectionable, and tending in extreme cases to break or fracture it, especially at a point between the striking part and the axis of swinging. The inertia of the presser head during the striking movement, and the impact upon the die, both have a tendency to force or bend upwardly the forward end of the head, this stress operating to create a strained condition in the metal composing the head, substantially from the free or forward end rearward and down to the foot of the extension. The result of this operating stress is to create, in the upper or outer parts of the head a compression strain, and in the lower or inner parts a tensile strain, the metal at the latter parts being actually stretched or tensioned, causing the tendency after many operations, as stated, to produce a fracture or break at any weak point, which little by little

may increase until causing a complete rupture or breakage of the head. The head therefore, as already explained, should have inherent strength to resist fracture, and rigidity to minimize bending, which latter impairs parallelism and interferes with a proper cutting action.

Under the principles pertaining to stresses in metal structures it is well understood that there may exist what may be termed a neutral axis or imaginary surface at a location between the portions under compression strain and the portions under tensile strain. This neutral axis need not be herein exactly located for purposes of description but will be understood to extend through the length of the head, about midway between its upper and lower portions, from the front to the rear, and around and down through the rear extension. It may be herein approximately located as extending at or preferably slightly below the division plane $x-x$ from front to rear, and then down in front of the division plane $y-y$, hereinafter to be referred to, that is to say at or slightly inside of the planes of division or demarcation between the outer and inner portions of the composite presser head.

The general plan of this invention therefore is to build up the presser head of a lower or inside aluminum portion, and an upper or outside iron portion, the two rigidly interconnected, and so designed with planes or surfaces of division whereat the two are joined, that the neutral axis of strain of the entire presser head, when in use, will fall approximately near to the division surface or planes; and preferably the neutral axis is slightly inside of the division surface so that no part of the iron component will be subjected to any but compression strains. In referring to aluminum here and hereafter is meant any suitable alloy, of light weight, and which is hard and rigid and possesses high tensile strength, such alloys having been produced by metallurgists and now well known as available for various mechanical purposes.

For facility of manufacture, and to minimize machining expense, the division surface preferably comprises two division planes, indicated as the planes $x-x$ and $y-y$, the former extending through the body of the pressing portion of the presser head from front to rear, and the latter extending downwardly through the length of the rear extension of the head. In connection with this arrangement of division planes, each component hereof, the iron component and the aluminum component, is designed and machined so that its points of union or connection with the other component will lie substantially in one or the other division plane, or at any rate parallel thereto, so that when the component is set up in the machine shop the planing operation is a substantially simple and rapid one. As will be observed the iron and aluminum

components preferably do not contact continuously throughout the division surface, but only at intermittent points, for example seven in number, as shown, thus minimizing the machining work and insuring a more accurate product. Another feature of preference is that the division planes $x-x$ and $y-y$ are at right angles to each other, so that when the machining has been accomplished in one plane the setting up and machining at the other plane will be more easily, accurately and expeditiously performed.

A presser head designed in accordance with the principles just described is illustrated in the four figures hereof constituting an example of the principles of the invention. To facilitate understanding of the drawings the aluminum component of the presser head is stippled to distinguish it from the iron component.

Referring first to the aluminum component or portion of the illustrated presser head, this comprises various integral parts, as follows. The so-called striking plate 70 is swingable to selected positions over the bed 12, and delivers the blow upon the die 17. To strengthen the edge part of the striking plate and to constitute a rim convenient to be handled the plate is shown provided with an upstanding short flange 71 extending around the front and rearwardly along both sides substantially to the rear of the striking part of the plate. Upstanding from the striking plate also is a transverse web 72, and to the rear of that a taller transverse web 73 which forms substantially a continuation of the rim 71.

These several webs and others to be described of course give stiffness and strength to the structure with minimum use of metal. No novelty is claimed in the design of a presser head involving a striking plate with integral flanges and webs, as this is a well understood matter of general structural design, and indeed cast iron presser heads have long been designed in this manner so as to minimize the volume and weight of metal, while attaining high rigidity and strength.

A fore-and-aft or longitudinal web 74 is shown also upstanding from the striking plate, along its center line, extending from the front rearward to the transverse web 72, while a continuation 75 thereof extends from transverse web 72 to transverse web 73, and this central web 72 is shown as formed with a horizontal top flange 76 giving added strength and stiffness. These webs, as seen in Fig. 3 are preferably extra thick, to improve the strength and rigidity to resist tensile stress.

With reference to the division plane $x-x$, the aluminum component of the presser is shown as having an enlargement or joining portion 77 at the front, adapted to receive steel bolts joining the iron and aluminum components at this first or front connection

point or junction 101. Similarly, at the rear of the web 74 and near the web 72 are shown opposite enlargements 78 adapted to receive connecting bolts, and their upper surfaces constituting the second junction 102. Again, near the transverse web 73 are opposite enlargements 79 adapted to receive such bolts, and with their upper surfaces at the third junction 103. Substantially this principle is continued throughout the fore-and-aft extent of the presser and around through the downward extension thereof. The aluminum component is rigidly connected with the iron component at each of the junction points 101, 102, 103, etc., and these three junction points as well as the one next to be described will be seen to present surfaces or planes coinciding with the division plane $x-x$. Preferably the heavy and light metal components of the presser head do not contact, nor extend to the division plane, between the junction points. Thus as seen in Fig. 1, the central web 74 is shown curved downwardly away from the division plane, while the top flange 76 of the web 75 is similarly bowed or curved downwardly between the enlargements 78 and 79. The same will be explained to be true also with the iron component of the presser. In this way metal not comprised in the bolted junction is kept well removed from the division plane and neutral axis, so as more effectually to apportion the strains, more especially to confine the tension strains to the aluminum component, approximately, and the compression strains to the iron component.

Rearward of the transverse web 73 the aluminum component is formed with a thick central web 80, the top of which is widened 40 into a flange 81, these extending rearwardly to where the contour is expanded into the form of a hollow cylinder 82, arranged to surround the post 18 of the clicker, with or without any bearing contact therewith. At 45 the two sides of part 82 are shown enlargements 83, to receive connecting bolts, these enlargements stiffened by fillet flanges 84, and being machined at their top sides in the plane $x-x$ to constitute junctions 104.

50 The aluminum structure, and the corresponding iron structure, in some types of clicker, might terminate substantially at the point thus far described, especially in cases where the presser head is rigidly clamped to the reciprocating post rather than rotating on the post. The invention however is shown in the Reece type of clicker and the description continues as follows.

To the rear of the cylindrical portion 82 the central web 85 takes a much thicker design, as seen in Figs. 2 and 4, and curves down into a downward extension constituting part of the extension 20. What may be considered as an extension of the striking plate 70 is the heavy downward flange 86, constitut-

ing the front flange of the web 85, these two parts in fact constituting the entire cross section of the aluminum component of the downward extension, as seen in Figs. 1 and 4. Near the top of these parts is an enlargement 76 87 for receiving horizontal connecting bolts and presenting a junction 105, this enlargement preferably having extended length and passing forwardly from the junction point to a point beyond and below the enlargement 75 83 already described.

At a point part way down below the enlargement 87 there is shown, on the web 85, an enlargement or lug 88 presenting a junction point 106, which, like the junction point 105, may have its surface lying in the division plane $y-y$, or at least near to and parallel with such plane. The lowermost extremity of the web 85 is shown formed with a substantial enlargement 89 presenting a junction 107 in the plane $y-y$ and arranged to receive connecting bolts. Finally, the lower ends of the web 85 and its flange 86, and the forward extension of the enlargement 89, are continued and shaped into a cylindrical portion 90 which may constitute or contain the bearing 21 already referred to by which the lower end of the downward extension is engaged in a rotary manner on the post 18.

Coming next to the iron component or portion of the illustrated presser, this comprises various parts which are largely complementary to the parts of the aluminum component, but are located wholly or mainly at the compression side of the neutral axis whereas the aluminum parts are at the tension side. The iron portions overlie or outwardly surround the aluminum portions, and this metal being well adapted to receive high compression strains without elastic bending or liability to fracture, the design may be considerably smaller in cross section, and therefore lighter, than would be the case if tensile strains were to be received.

The iron component comprises, in the illustrated embodiment, a top or outer flange 110, which is laterally crowned or convexed, and is longitudinally convexly curved analogously to the design of presser head in said prior patent. It is considerably thinner in cross section than the striking plate 70, and narrower. At its forward extremity the iron component is formed with an enlargement 111 directly above the aluminum enlargement 77 and machined to fit accurately with the latter at the junction 101, preferably in the division plane $x-x$; and a pair of steel bolts 101* are shown at symmetrically opposite positions, passing through the enlargement 111 into the enlargement 77 and firmly uniting the two components at this junction point.

Below the forward portion of the iron top flange 110, in what may be termed the first panel, is a vertical central web 112. This ex-

- tends from the front rearwardly to a transverse web 113 which stands down from the top flange. The lower edge of the web 112 is shown formed as a horizontal flange 114 which stiffens the web, and is arched upwardly away from the division plane $x-x$, also laterally incurved, as seen in dotted lines in the plan view Fig. 2. The design and contour of these and the remaining portions 5 of the iron component are determined by the requirement of minimum mass consistent with adequate strength for compression strain, and rigidity against upward bending. Thus the central web 112 is relatively thin, 10 and as seen in Fig. 3 may be but one third of the thickness of the complementary aluminum tension web 74, thus cutting down the volume of iron and mass of the presser as a whole.
- 15 Near the transverse web 113 the iron component is enlarged at 115 at points opposite the aluminum enlargements 78, the two being interconnected at the junction 102 by steel bolts 102^a.
- 20 In the second panel, similarly, is a vertical central web 116 extending rearwardly to a transverse web 117, the central web having an arched and incurved flange 118, as shown in Fig. 2, and the opposite aluminum flange 25 76 may be shaped the same. Adjacent the web 117 are shown enlargements 119 opposite the aluminum enlargements 79, the two meeting in the plane $x-x$ at the junction point 103 and being firmly interconnected by bolts 30 103^a.
- 35 Rearward from the transverse flange 117 is shown a central web 120 constituting substantially a continuation of the webs 112 and 116 and extending to a cylindrical portion 40 122 surrounding the clicker post 18 and constituting a bearing engaging the same, and shaped to engage the shoulder 22 of the post, these parts being sufficiently heavy to stand the shocks received during reciprocation and impact. At each lateral side of the cylindrical part 122 is an enlargement 123 arranged opposite to the aluminum enlargements 83, the two meeting at the junction 104 and being interconnected by bolts 104^a.
- 45 The importance of reducing the iron cross section and mass decreases with the approach to the axis of swinging, namely the axis of post 18, for the reason that the inertia which requires muscular effort to overcome, both 50 in starting and terminating the swinging, is a moment or rotary force. For this reason the free or forward ends of pressers have always been made lighter than the rear or axial parts. Metal near the axis moves but little during the swinging, and its inertia offers but little opposition to the swinging effort. For this reason the cylindrical iron portion 122 should be made safely heavy. In 55 the Reece type clicker considerable inertia is obviated by the fact that the down and up

moving post 18, which carries the presser, does not rotate with the presser, and so does not require to be moved in the swinging of the presser as in certain other types of clicker.

70 Beyond or behind the parts described is a continuation comprising a thin vertical web 124 extending inwardly from the downcurved portion of the crowned flange 110, this web having a notch at 125 to prevent possible tension strain and minimize any tendency to a fracture at this danger point. The flange 110 and web 124 are formed into opposite enlargements 126 which are complementary to the aluminum enlargements 87 and meet them at 75 the junction 105, where they are securely and rigidly tied together by bolts 105^a. From this point downwardly the iron component comprises a convex extension 127 of the flange 110 and a thin extension 128 of the web 124. The web 128 has a portion 129 adapted to contact the lug 88 of the aluminum web 85 at 80 the junction 106. At the foot of the iron parts the web and flange terminate with an enlargement 130 complementary to the aluminum enlargement 89, and which connects with the same at the junction 107 in the plane $y-y$, being rigidly attached by bolts 107^a passed through the iron part and threaded deeply into the aluminum part.

90 The particular embodiment thus described may be greatly varied within the principle of the invention, which may be in one aspect stated as a power press of the clicker type comprising the bed for supporting the leather, with mechanism to depress and raise the presser, and the presser, fitted to be moved to selected positions over the bed, and built up of longitudinally contiguous components, one of which is light and the other is low priced, and both are strong and rigid, and unitarily connected. A clicker presser head thus described possesses the chief advantages of the present invention. The component which is light may be otherwise described as a light rigid alloy, and the low priced component as composed of base metal. The alloy referred to may be any standard alloy, with a substantial component of aluminum, and known to possess the required qualities. The principal embodiments of the invention will possess the arrangement wherein the lower or inner component is composed of a light alloy which is hard and rigid and of high tensile strength, while the upper or outer component is of low priced or base metal, rigid and with high compression strength, so that in handling the stresses encountered in practice the light alloy will resist the tensile strains while the rigid base metal or iron component will resist the compression strains. In either of these aspects the presser may be of a contour terminating at the level of the striking plate, without the downward rear extension which 100 characterizes the Reece type of clicker.

105 110 115 120 125 130

The described presser may be constructed almost as light as one which is entirely of aluminum. This is due to the fact that the iron component has only the compression strains to handle so that its webs may be made relatively thin. The presser will be as strong or stronger than an all aluminum presser unless indeed the latter is made of heavier dimensions, and it will require no struts or braces as has sometimes been found necessary with all aluminum presses. The presser hereof is light enough to ease the muscular effort, but is not so light as to impair the effectiveness of the cutting blow, and it avoids the present high first cost of an all aluminum presser.

It will be noticed that there are no joints or contact points between the contiguous components of the presser excepting at the seven junction joints, at six of which the components are firmly and rigidly interconnected by strong steel bolts or the equivalent; and that there are no joints of any kind at the danger points closely in front of and to the rear of the cylindrical parts surrounding the vertical post. There are preferably no joints within either of the two components, the iron component being integrally continuous from one longitudinal end to the other, and the same with the aluminum component. Between the connecting or junction points 101, 102, etc., the components are shaped concavely so as to leave gaps or spaces, thus relieving the components of any communicated strain except at the junction points. The lug 88 on the downward aluminum extension and the complementary portion 129 of the iron component are in contact without being bolted. This contact, or the lug or pad 88, is located fairly high in the downward extension for the purpose of minimizing the tendency to strain at this point. Without this pad, the tendency to bend or buckle forwardly might result in injurious strain. The aluminum component takes the tensile strain at this part of the presser, and the iron component takes the compression strain, as already described, but with this pad the aluminum component further aids in the resistance against forward bending or buckling of the iron component, which otherwise might introduce a tensile strain at the forward edge of the latter, and in extreme cases result in injury; while the aluminum component is relieved of compression strain at its rear edge. At the same time, being unbolted, the parts may relatively slide at the junction 106, and thus avoid introducing any shearing action at the junctions 105 and 107 above and below.

If desired, lateral dovetail interconnections might be introduced at various junction points between the two components, although the flat junctions arranged in or parallel to division planes $x-x$ and $y-y$ are preferable,

and greatly simplify the process of manufacture.

In one aspect the iron or outer component may be considered as a backing portion, having compressive strength, and reinforcing the aluminum inner or striking portion, which in turn reinforces the backing portion, giving a mutual cooperation attaining the objects of this invention. The clicker hereof can be used for other than cutting-out operations on leather, etc.; for example stamping or embossing the same, with or without a loose die.

There has thus been described a press for cutting or punching sheet material embodying the principles and attaining the objects of the present invention. Since several matters of combination, construction, arrangement, design and detail may be variously modified without departing from the principles of the invention it is not intended to limit the invention to such matters except so far as set forth in the appended claims.

What is claimed is:

1. A power press of the clicker type for operating upon leather or other sheet material comprising the bed for supporting the material flatwise, mechanism to depress and raise the presser, and a presser laterally swingable to selected operative positions over the bed, and built up of upper and lower longitudinal components unitarily interconnected in longitudinal surface contact along a division surface proximate to the neutral axis of strain of the presser, the lower component consisting of a relatively light metal alloy of high surface hardness and tensile strength, and the upper component consisting of a relatively heavy metal of high rigidity and compressive strength, whereby such components mutually reinforce each other against the strains encountered in practical operation.

2. A power press of the clicker type for operating upon leather or other sheet material comprising the bed for supporting the material, mechanism to depress and raise the presser, and a presser laterally swingable to selected positions over the bed, and built up of upper and lower components unitarily interconnected in longitudinal contact along a division line proximate to the neutral axis of strain of the presser, the lower component consisting of a metal of high tensile strength, the upper component consisting of a different metal of high rigidity and compressive strength and one of said metals having much lower density than the other, whereby the combined united components present high cooperative resistance to strains and a moderate total mass.

In testimony whereof, I have affixed my signature hereto.

JOHN ROGER OLIVER.
